GARMENT PARTS AND FOLDLINE-FORMING
MEANS THEREFOR

Benjamin Liebowitz, Lewisboro, N. Y., assignor
to Trubenizing Process Corporation, New York,
N. Y., a corporation of New York

Application March 31, 1950, Serial No. 153,050

12 Claims. (Cl. 2—131)

1

The invention disclosed in this specification relates to garment parts, particularly men's collars, and to foldline-forming means therefor, and is an improved modification of the invention disclosed in my patent application Serial No. 79,757, filed March 5, 1949, now abandoned, for Collars and the Manufacture Thereof. The invention will be described in connection with men's collars, particularly so-called "fused" collars, which is its principal field of application at the present time.

Men's collars, whether separate or attached to shirts, are in most instances made in two parts, viz., a so-called collartop and a so-called collarband, each part comprising generally three plies. In the course of manufacture these two parts are sewn together along what is known as the collarbanding seam, and the resulting heavy seam (there are nine plies of material in the region of the seam) at the juncture of these two parts provides a foldline guide for folding down of the collartop portion after each laundering. When, however, the plies of the collartop and the band portions are cut in one piece in the manufacture of a one piece collar, which is the principal subject of my present invention, there is no collarbanding seam and it is highly desirable, or even necessary for proper functioning of the collar, to provide foldline-forming means along which the collar will be automatically folded after each laundering. (So-called sport shirts are not included in this discussion.)

In my Patent No. 2,118,407 I have disclosed foldline-forming means applicable to garment parts and having particular applicability to collars of the fused type whereby a resist material or equivalently a thin strip of tissue is interposed between two plies which are otherwise fused together, thereby defining a foldline along a narrow zone where the resist material or tissue is applied and prevents the fusion of the plies. As applied to collars experience showed, however, that the expedient disclosed in my patent was not easy to apply and moreover resulted in a product whose band portion adjacent the foldline lacked firmness.

In my copending application mentioned above I have disclosed an improvement on that which is disclosed in my Patent No. 2,118,407, the improvement residing in the provision of novel foldline-forming means for one-piece fused collars comprising a preformed strip of fabric or tape, the main portion of which preferably carries latent adhesive material; and a marginal edge of which is treated with resist material. The main portion of the tape is firmly secured

2

in the band portion of the collar by the adhesive carried thereby or by the adhesive carried by the lining ply or both (and by stitches also if desired), and the resist-treated marginal portion extends into the foldline with the resist-treated face in contact with the adhesive-bearing lining of the whole collar. As a result of this structure, the portion of the band adjacent the foldline, after the fusing operation, is stiffened relative to the rest of the collar. Thus in preferred practice there are four plies all adhesively united in the collarband, whereas the foldline portion determined by the resist-treated edge of said tape is, after the resist has been washed out, softer or more flexible than the rest of the collar, because, of its four plies, two are unadhered and only two are adhesively united; the rest of the collar, exclusive of seamed edges, consisting of three plies all adhesively united. This tape scheme, moreover, has the decided advantage that, with proper techniques, it is easily applied.

Very good results have been obtained utilizing the tape or strip as described in my copending application, but when the collar thus made is treated carelessly or abusively in laundering, there is a tendency for the unfused region along the foldline to spread into the band portion and also into the collartop portion.

The primary objects of the improvement described herein are to oppose this spread of defusion and at the same time to make the foldline determined by the strip still more definite and precise. Another object is to provide a fabric tape whose construction has relatively increased flexibility in the zone disposed along the foldline. Other objects and advantages will become apparent from the following description.

According to my present invention the foregoing objects have been accomplished by the provision of a novel foldline-forming strip or tape and the incorporation of same in a one-piece collar of the fused type. This strip or tape is characterized by the fact that it not only has an adhesive carrying body portion adapted to stiffen the collarband, but also an adhesive-carrying marginal portion which extends beyond the foldline into the collartop and which is adapted to become firmly adherent in this portion of the collar. Between these two stiffened portions there is a relatively more flexible zone which is narrow but of substantial width and which is adapted to be disposed along the collar foldline, with the result that in the finished fused collar the strip or tape is firmly

adherent not only in the collarband portion, but also in the collartop portion on the opposite side of the foldline, while increased flexibility is provided along the collar foldline. For maximum flexibility the zone of the strip which falls along the collar foldline has resist material applied thereto so that this portion of the strip will not adhere to the adhesive carrying lining ply of the fused collar. Preferably the new foldline-forming strip comprises longitudinally extending strands of latent adhesive yarns in the body portion adapted to fall in the collarband, a zone contiguous with said body portion which is free of the latent adhesive yarns and which is adapted to fall along the collar foldline, and a few longitudinally extending strands of the latent adhesive yarns along and adjacent the free edge of said adhesive-free zone. Preferably the latent adhesive yarns along and adjacent the margin extending into the collartop are disposed in more closely contiguous relation than is the case in the body portion of the strip. Discontinuity of stiffness along the foldline also can be afforded or accentuated according to this invention by so constructing the fabric of the tape that a marginal zone thereof falling along the foldline has relatively increased flexibility.

My invention will be better understood with reference to the drawings which show a typical illustrative embodiment thereof and in which:

Fig. 1 is a plan view of a one-piece collar showing the foldline-forming strip dotted;

Fig. 2 is a schematic cross-sectional showing on the line II—II of Fig. 1;

Fig. 3 is an enlarged plan view of a portion of the collar shown in Fig. 1 showing the different zones of the foldline-forming strip;

Fig. 4 is an enlargement of the portion of the cross-section of Fig. 2 at which the foldline-forming strip is disposed;

Fig. 5 is a schematic plan view of the preferred foldline-forming strip greatly enlarged, in which the latent adhesive yarns are shown heavy and the non-adhesive yarns are shown light; and

Fig. 6 is a cross-section on the line VI—VI of Fig. 5 in which the latent adhesive yarns are again shown large and the ordinary cotton yarns are shown small.

Referring to the drawings, a one-piece collar which is generally indicated by the reference character 10, is shown as comprising three plies, viz., a face ply 11, a lining ply 12, and a back ply 13. Between the back ply 13 and the lining ply 12 is the novel foldline-forming strip or tape of this invention which is indicated generally by the reference character 14. The lining ply 12 bears adhesive material adapted to cause it to become adherently bonded or "fused" to the face ply and the back ply wherever the latter are in contact with the lining ply. The adhesive is ordinarily carried by the lining ply in the form of yarns, such as cellulose acetate, which are soluble in organic solvents and which can be activated to impart adhesiveness thereto for bonding the lining ply with the plies in contact therewith by solvent application and heat and pressure in the conventional manner employed in the manufacture of collars of the fused type. Alternatively the adhesive may be carried by the lining ply in the form of a coating.

The general nature and purpose of the novel foldline-forming strip 14 are shown and illustrated in greater detail in Figs. 3 and 4. The main or body portion 14c of the foldline-form-

ing strip carries latent adhesive material so that it can become bonded with the back ply 13 when the collar assembly is fused. The portion 14c will in any event also become bonded with the lining ply 12 due to the adhesive carried by the lining ply. The narrow marginal portion 14a also carries the latent adhesive for causing it to become bonded or fused to the back ply 13, and like the body portion 14c it in any case becomes bonded to the adhesive-carrying lining ply 12 when the collar is fused. Between the portions 14c and 14a is the zone 14b which, while narrow, possesses substantial width, say $\frac{1}{8}$ ", more or less. The zone 14b is of such character that it will not become adherent to the back ply 13 when the collar is fused. This result may be most readily obtained by omission of any adhesive in the region of the zone 14b, although if this portion of the strip 14 does carry adhesive the surface of the strip facing the back ply 13 may be covered with resist material in the region of the zone 14b. The zone 14b will adhere to the adhesive-carrying lining ply 12 when the collar is fused whether the said zone 14b does or does not carry an adhesive, but such adhesion of the zone 14b to the lining ply can, if desired, be prevented by application of resist material to the surface thereof facing the lining ply 12.

In the finished collar the body portion 14c is located in the collarband and is fused both to the lining ply and to the back ply thus imparting increased stiffness to the collarband. The zone 14b of the strip 14 falls along the desired location of the foldline between the collarband and collartop portions of the finished collar, and because at least the surface thereof facing the back ply 13 is non-adherent to the back ply, the zone 14b provides a narrow elongated region along the collar foldline which is of increased flexibility as compared with the collarband where the body portion 14c of the strip 14 is located. The marginal portion 14a extends slightly into the collartop portion of the collar and is fused to both the lining ply 12 and the back ply 13, thus securely anchoring this margin of the strip 14 so as to effectively prevent defusion and spreading of the more flexible zone laterally from the collar foldline and so as to accurately define and limit the width of the more flexible zone along which the collar is to be folded after laundering. In the finished collar the lining ply is, of course, fused to the face ply 11 at all points and is fused to the back ply 13 except where the strip 14 is interposed between the lining ply and the back ply.

If still greater flexibility along the collar foldline is desired then the zone 14b of the strip 14 may be made substantially non-adherent not only with the back ply 13, but also with the lining ply 12 by applying resist material to the surface thereof facing the lining ply.

A preferred form of foldline-forming tape is shown in detail in Figs. 5 and 6. In the embodiment shown the tape 14 is provided with a selavage edge comprising a few (in the drawing, two) latently adhesive warp yarns A1 (the marginal portion 14a), then a series of ordinary cotton warp yarns C1 (the zone 14b), then a few adhesive warp yarns A2 (e. g. two) and then a sequence of warp yarn repeats each of which comprises two cotton yarns C and one adhesive yarn A, ending at the bottom of the figure with a cotton yarn (the yarns A2 and the repeats of A and C together constituting the body por-

tion 14c). A suitable adhesive yarn is cellulose acetate. The cross-section of the tape shown in Fig. 6 corresponds with the plan shown in Fig. 5. The material marked D in Fig. 6 indicates that the cotton yarns in this portion (the zone 14b) are covered with resist material at least on one side to prevent adhesion between these cotton yarns and the lining 12, which lining carries adhesive substance for the purpose of fusing or laminating the three plies into a single ply. The weft yarn is of cotton or other non-soluble substance, e. g. viscose, and is schematically indicated at w only at one end of Fig. 5. The weave itself may be an ordinary plain weave.

The present invention differs from that shown in my copending application above mentioned mainly in the addition of the adhesive-carrying marginal portion 14a which in Figs. 5 and 6 comprises the two topmost yarns A1 along the upper selvage edge which projects into the collar-top. This modification is by no means trivial or obvious.

Any portion of the foldline tape projecting into the collartop may be such as to be noticed from the outside and hence objectionable unless means are employed to avoid this showing or at least to minimize it. I preferably use for the uppermost yarns A1 not more than two or three strands of cellulose acetate, each of about 300 denier or less. If more extensive or bulky construction is utilized the effect on the external collar is noticeable in that it changes the profile of the collar cross-section and thereby throws visible shadows in the neighborhood of the foldline which are not desirable. However, I have found that by using only two strands of cellulose acetate, for example, each of 300 denier, then the shadow effect mentioned above is so slight as to pass unnoticed. In other words, I have demonstrated that it is possible to have a portion of the foldline-forming means actually project slightly into the collartop without incurring objectionably noticeable effects. It is preferable in any case that the width of the strip margin extending into the collartop be not substantially greater than the width of the zone which determines the location of the collar foldline.

It is also preferable according to my present disclosure to have the double strand of cellulose acetate yarns A2 shown in Figs. 5 and 6 at the junction between the adhesive-free zone 14b of the tape and the adhesive-bearing body portion 14c. This doubling of the acetate strand (say each of 300 denier) is, of course, not noticed from the outside since it is in the band portion of the finished collar and improves the adhesion to a considerable extent along this region, thereby reducing the tendency for defusion to spread along the back ply from the unadhered zone 14b of the tape to other parts where adhesion is wanted.

When the strip or tape 14 shown in Figs. 5 and 6 is employed in the manufacture of a fused one-piece collar it is located in the collar in the manner shown in Figs. 1 to 4; and the portions 14a, 14b and 14c thereof occupy the positions shown in Figs. 3 and 4 and have the functions ascribed to them in the foregoing description with reference to Figs. 3 and 4. When the resist D is applied to the surface of the zone 14b that faces the lining ply then the zone 14b will be essentially non-adherent both to the lining ply 12 and to the back ply 13. Methods and apparatus for accurately placing the tape 14 with respect to the contours of the collars are disclosed in my copending application Serial No. 79,758,

6
filed March 5, 1949, for Method and Apparatus for Making Collars or the Like.

The difference in structure between the tape or strip described herein and that described in my copending application Serial No. 79,757 results in a significant possible difference in use, viz., that whereas the tape of my copending application requires the use of resist for its best functioning, the tape described herein may be used without resist facing the lining ply because the surface of the zone 14b facing the back ply 13 is not adherent to the back ply 13 and because of the fact that this adhesive-free or otherwise non-adherent region of the tape lies between regions having relatively large amounts of adhesive substance, with the result that if a collar is once properly folded down, it will subsequently tend to fold along the same foldline determined by the non-adherent region of the tape even if no resist is used between the zone 14b and the adhesive-carrying lining ply 12. This is because the portion of the collar occupied by the zone 14b of the strip 14 is more flexible than the stiffened portion of the band adjacent to it on one side and the stiffened portion of the collartop adjacent to it on the other side. The tendency for the collar to fold along this more flexible region of the tape can, and preferably should, be furthered by weaving this region of lighter warp yarns C1 and/or of warp yarns spaced farther apart. Alternatively, the yarns C1 in the adhesive-free region may be of Bemberg or viscose, instead of cotton, say 100 denier; these light Bemberg or viscose yarns having a desirable effect in making the foldline region more flexible even when no resist is used.

As described in my copending application Serial No. 79,757, the adhesive-bearing portion of the tape or strip 14 may be plasticized so as to facilitate temporary adhesion of said strip to the interlining 12 in the course of manufacture. I have found, however, that when resist material is employed it is also possible to dispense with the plasticizer and to use the resist itself as a means for temporarily sticking the tape or strip to the lining. If a resist is employed a convenient resist material to use is a water-soluble cellulose ether, which creates a thin strong film that prevents fusion and that is eliminated on the first washing.

While a specific form of foldline-forming strip has been shown and illustrated wherein the adhesive is carried thereby in the form of latent adhesive yarns woven therein, the new foldline-forming tape may take other forms that embody and utilize the principles of the invention described hereinabove. Thus, while the control of the location and nature of the different portions of the special foldline-forming strip can be realized to advantage by using a tape or strip wherein the latent adhesive is in the form of yarns or strands woven therein, the latent adhesive may be carried by the strip in other ways as, for example, in the form of a coating; and an inherently non-adherent zone may be provided between the adjacent adhesive zones either by absence of adhesive therein or by use of resist material. Moreover, the feature of constructing the fabric of the strip or tape so that the fabric possesses relatively increased flexibility in a zone adjacent an edge thereof that falls along the collar foldline is of general utility and advantage and may be embodied in strip and fused collar embodiments other than those exemplified hereinabove, e. g., such as those I have disclosed in my application Serial No. 79,757. When the

strip is so constructed the construction of the fabric in and of itself provides discontinuity of stiffness between the fabric of the strip in such zone of relatively greater flexibility and the fabric of the strip which is of inherently less flexibility and greater stiffness that borders one or both sides of said zone.

I claim:

1. As an article of manufacture, a preformed foldline-forming strip of fabric at least one surface of which comprises a body portion carrying a latent activatable adhesive, a narrow non-adhesive zone of the order of $\frac{1}{8}$ inch in width adjacent one edge of said strip, and a narrow marginal portion which is not of substantially greater width than said zone and which carries latent activatable adhesive between said zone and said edge of said strip, said zone being disposed between and bordered by said body portion and said marginal portion, said strip of fabric on the opposite surface thereof being coated with resist material which is disposed along and is substantially confined to that portion of said opposite surface corresponding to said zone, and said strip being adapted to be disposed between plies of a collar having a collarband portion and a collartop portion for disposition predominantly in the collarband portion thereof with said zone disposed along the foldline between the collartop and collarband portions of the collar.

2. As an article of manufacture, a foldline-forming strip of fabric according to claim 1 wherein the fabric of said strip in the region of said narrow non-adhesive zone is inherently of substantially more flexible construction as compared with the fabric of said strip in the region of said body portion.

3. As an article of manufacture, a preformed foldline-forming strip of fabric adapted for adherent application between the adhesive-carrying lining and another fabric ply of a fused collar for determining the foldline between the collarband and collartop portions of the collar, said strip comprising longitudinally extending warp yarns composed of activatable adhesive material along and adjacent each edge of said strip and in the body portion thereof except for a zone of the order of $\frac{1}{8}$ inch in width which is disposed substantially parallel to one edge thereof and spaced from said edge by a distance not substantially greater than the width of said zone and which is substantially free of yarns composed of activatable adhesive material, and said strip in said body portion thereof other than said zone comprising adhesive free warp yarns disposed in staggered relation with respect to said yarns composed of activatable adhesive material.

4. As an article of manufacture, a foldline-forming strip according to claim 3 wherein there are from two to three closely contiguous longitudinally extending yarns of activatable adhesive material constituting essentially the width of the portion of said strip between said zone and the adjacent edge of said strip, said yarns not being substantially greater than 300 denier.

5. As an article of manufacture, a foldline-forming strip according to claim 3 wherein the fabric constituting the region of said zone is inherently more flexible than the fabric constituting the other portions of said strip.

6. As an article of manufacture, a preformed foldline-forming strip of fabric adapted for adherent application between the adhesive-carrying lining and another fabric ply of a fused collar for determining the foldline between the collar-

band and collartop portions of the collar, said strip comprising longitudinally extending warp yarns composed of activatable adhesive material along and adjacent each edge of said strip and in the body portion thereof except for a zone of the order of $\frac{1}{8}$ inch in width which is disposed substantially parallel to one edge thereof and spaced from said edge by a distance not substantially greater than the width of said zone and which is free of yarns composed of activatable adhesive material, said zone presenting a resist material on at least one of the surfaces thereof adapted to prevent adhesion of said zone to the adhesive-carrying lining of the collar, and said strip in said body portion thereof other than said zone comprising adhesive free warp yarns disposed in staggered relation with respect to said yarns composed of activatable adhesive material.

7. A fused collar having a collarband portion and a collartop portion and comprising a plurality of fabric plies including a lining ply that is fused to the fabric of at least one of the plies in contact therewith in the collarband and collartop portions of the collar, said collar comprising a strip of fabric disposed between and in contact with two of said fabric plies one of which is said lining ply, said strip of fabric being disposed predominantly in the collarband portion of the collar and having a margin thereof disposed in the collartop portion of the collar adjacent the foldline between the collarband and collartop portions of the collar, said strip of fabric being fused to the fabric plies in contact with the opposite surfaces thereof in the region thereof disposed in the collarband portion of the collar and in the region thereof disposed in the collartop portion of the collar and being fused at most to one only of said fabric plies in a zone of narrow but substantial width bordered by said regions and disposed along the foldline between the collarband and collartop portions of the collar.

8. A fused collar having a collarband portion and a collartop portion and comprising a plurality of fabric plies including a lining ply, said collar comprising a strip of fabric disposed between and in contact with two of said fabric plies one of which is said lining ply and which are fused directly together except where said strip of fabric is disposed therebetween, said strip of fabric being disposed predominantly in the collarband portion of the collar and having a margin thereof disposed in the collartop portion of the collar adjacent the foldline between said collarband and collartop portions of the collar, said strip of fabric being fused to at least one of said plies only in the region thereof disposed in the collarband portion of the collar and in the region thereof adjacent said margin of said strip disposed in the collartop portion of the collar leaving a zone thereof of narrow but substantial width between and bordered by said regions that is in opposed free relation to said ply, said zone being disposed along the foldline between the collarband and collartop portions of the collar.

9. A fused collar according to claim 7 wherein the portion of said strip extending into the collartop portion of the collar and fused to the collar plies on the opposite sides thereof is of the order of width and thickness provided by two to three contiguous yarns not greater than about 300 denier.

10. A one-piece fused collar having a collartop portion, a collarband portion and comprising a face ply, a lining ply and a back ply, said collar comprising a strip of fabric which is longitudi-

nally disposed between said lining ply and said back ply and predominantly in the collarband portion of the collar with one margin thereof extending slightly into the collartop portion of the collar, said strip being fused to said back ply except in a zone of narrow but substantial width along the foldline between the collartop and collarband portions of the collar adjacent to said margin of said strip that extends into said collartop and being fused to said lining ply at least in the regions of said strip disposed on the opposite sides of said foldline, said lining ply being fused throughout to said face ply and being fused to said back ply except where said strip is interposed between said lining ply and said back 15
ply, said zone providing a more flexible zone between bordering zones of greater stiffness and thereby defining the location of the collar foldline.

11. A one-piece collar according to claim 10 20
wherein said strip is fused to said lining ply except in the location of said zone along the foldline between the collartop and collarband portions of the collar adjacent to said margin of said strip that extends into said collartop. 25

12. A one-piece collar according to claim 10
wherein the fabric of said strip in the region of said narrow zone extending along said foldline is inherently of substantially more flexible construction as compared with the fabric of said strip in the region which is fused to said lining 5
ply and to said back ply in the collarband portion of the collar.
